UNITED STATES PATENT OFFICE

137,441

DESIGN FOR A BINOCULAR OR THE LIKE

John R. Miles, West Englewood, N. J., assignor to
Bendix Aviation Corporation, South Bend, Ind.,
a corporation of Delaware

Application September 16, 1943, Serial No. 111,141

Term of patent 14 years

To all whom it may concern:

Be it known that I, John R. Miles, a citizen of the United States, residing at West Englewood, county of Bergen, State of New Jersey, have invented a new, original, and ornamental Design for a Binocular or the like, of which the following is a specification, reference being had to the accompanying drawing, forming part thereof, in which:

Figure 1 is a side elevational view of a binocular or the like;

Figure 2 is a top perspective view looking from the eye pieces; and

Figure 3 is a side elevational view of the opposite side of the binocular or the like, showing my new design.

I claim:

The ornamental design for a binocular or the like, as shown.

JOHN R. MILES.
